UNITED STATES PATENT OFFICE.

THEODORE J. KOVEN, OF JERSEY CITY, NEW JERSEY.

EXHAUST-VALVE FOR INTERNAL-COMBUSTION ENGINES.

975,255.

Specification of Letters Patent.

Patented Nov. 8, 1910.

Application filed February 23, 1909. Serial No. 479,347.

To all whom it may concern:

Be it known that I, THEODORE JULIUS KOVEN, a citizen of the United States, and a resident of Jersey City, in the county of Hudson and State of New Jersey, have invented a new and Improved Exhaust-Valve for Internal-Combustion Engines, of which the following is a full, clear, and exact description.

10. The object of the invention is to provide a new and improved exhaust valve for internal combustion engines, arranged to keep the valve cool and thus prevent the accumulation of soot and premature explosions.

15. In order to cool the valve, a cooling medium, such as water, is circulated through the valve, and the inlet and outlet for the cooling medium are arranged so as not to interfere with the proper working of the 20 valve.

25. A practical embodiment of the invention is represented in the accompanying drawings forming a part of this specification, in which similar characters of reference indicate corresponding parts in all the views.

Figure 1 is a sectional side elevation of the improvement; Fig. 2 is an enlarged sectional plan view of the valve on the line 2-2 of Fig. 1; and Fig. 3 is an enlarged 30 plan view of the coupling.

An internal combustion engine A, of any approved construction, is provided with the usual exhaust chamber B, provided with a valve seat C adapted to be opened and closed 35 by an exhaust valve D, having its stem D' mounted to slide in a bearing E forming part of the engine A at the exhaust B'. The outer end of the valve stem D' is provided with a collar F, on which presses one end of a 40 spring G, resting with its other end on the bearing E, so as to normally hold the exhaust valve D to its seat C. The exhaust valve D is opened in the usual manner, to allow the products of combustion to exhaust 45 at a proper time.

The valve D is made hollow, that is, is formed with a chamber D² connected with the inlet passage D³ and the outlet passage D⁴ extending in the hollow stem D', and the 50 inlet passage D³ has its discharge end D⁵ extending downwardly and laterally within the chamber D², so that the exhaust of the passage D³ is a distance below the entrance to the outlet passage D⁴. Now by the arrangement described, the cooling medium passing through the passage D³ is discharged

by the end D⁵ into the chamber D², in such a manner as to produce a whirling of the cooling medium within the chamber D², thus uniformly cooling the entire valve D. The 60 cooling medium after having thus circulated in the chamber D² passes into the outlet passage D⁴.

Near the upper end of the valve stem D' at the upper terminals of the passages D³, 65 D⁴ is arranged a coupling H, having nipples H', H² connecting with the upper ends of the passages D³ and D⁴, as plainly indicated in Fig. 1. The nipple H' is connected by a hose or a like flexible connection I with a 70 nipple K' on a supply pipe K connected with a suitable cooling medium supply, the said pipe K being supported on a suitable bracket L attached to the engine A. Within the pipe K is arranged a screen N to screen 75 the cooling medium, thus preventing clogging of the valve by impurities contained in the cooling medium.

The nipple H² is connected by a hose or other flexible connection J with the nipple O' of a discharge pipe O, leading to a radiator, reservoir or other place of discharge, the pipe O being supported on a bracket L' attached to the engine A. Now by the arrangement described, a circulating pump or 80 other device forces the cooling medium through the pipe K, flexible connection I and nipple H' into the inlet passage D³ and down the same into the chamber D², to cool the valve D uniformly by circulating therein, as previously explained, the cooling medium finally passing out of the chamber D² and up through the passage D⁴ into the nipple H², and from the latter by the flexible 85 connection J, nipple O' and pipe O to a suitable place of discharge. By having the flexible connections I and J, it is evident that the valve D may be readily opened and closed without interference, as the connections I and J give sufficiently for the purpose. 90

The coupling H is preferably made in two sections clamped on the stem D' by screws, as indicated in Fig. 3, and the coupling connections are provided with pins H³ 105 engaging the corresponding recesses in the stem D' to hold the coupling against accidental displacement.

Although I prefer the construction of the coupling H, as described and shown in the drawings, it is evident that I do not limit myself to this detailed construction. 110

Having thus described my invention, I claim as new and desire to secure by Letters Patent:

A device for cooling valves of explosion engines comprising in combination a hollow valve, a stem connected therewith and having a plurality of longitudinal passages communicating with the interior of the valve, the inlet passage having a nipple extending in the said valve, the extension curving laterally away from the outlet passage, a bracket at each side of the valve, a supply pipe supported on the bracket adja-

cent to the inlet passage, a discharge pipe supported on the bracket adjacent to the outlet passage, and a flexible connection between each of said pipes and the adjacent passage.

In testimony whereof I have signed my name to this specification in the presence of two subscribing witnesses.

THEODORE J. KOVEN.
